(57) **CLAIM**

The ornamental designs for a low profile adapter mount for .22 rail and picatinny/weaver rail, as shown and described.

DESCRIPTION

FIG. 1 is an isometric perspective view of the first embodiment of low profile adapter mount for .22 rail and picatinny/weaver rail

FIG. 2 is a front view of adapter mount of FIG. 1

FIG. 3 is a rear view of adapter mount of FIG. 1

FIG. 4 is a right view of adapter mount of FIG. 1

FIG. 5 is a left view of adapter mount of FIG. 1

FIG. 6 is a top view of adapter mount of FIG. 1

FIG. 7 is a bottom view of adapter mount of FIG. 1

FIG. 8 is an isometric perspective view of the second embodiment of low profile adapter mount for .22 rail and picatinny/weaver rail

FIG. 9 is a front view of adapter mount of FIG. 8

FIG. 10 is a left view of adapter mount of FIG. 8

FIG. 11 is a top view of adapter mount of FIG. 8

FIG. 12 is a bottom view of adapter mount of FIG. 8

FIG. 13 is an isometric perspective view of the third embodiment of low profile adapter mount for .22 rail and picatinny/weaver rail; and,

FIG. 14 is a front view of adapter mount of FIG. 13.
